UNITED STATES PATENT OFFICE

105,622

DESIGN FOR A PENCIL

Martin E. Trolle, St. Paul, Minn., assignor to
Brown & Bigelow, St. Paul, Minn., a corpora-
tion of Minnesota

Application November 16, 1935, Serial No. 59,605

Term of patent 3½ years

To all whom it may concern:

Be it known that I, Martin E. Trolle, a citizen of the United States, residing at St. Paul, county of Ramsey, and State of Minnesota, have invented a new, original, and ornamental Design for Pencils, of which the following is a specification, reference being had to the accompanying drawing forming part thereof:

Figure 1 is a front elevational view of a pencil, showing my new design.

Figure 2 is a side elevational view.

Figure 3 is an end view, looking toward the head of the pencil.

Figure 4 is an end view, looking toward the writing tip of the pencil.

My design comprises a pencil, substantially diamond-shaped in cross section, and having a line parallel the edge thereof on the flat sides of the pencil. The design also includes an enlarged cylindrical operating knob having a cone-shaped top thereon, and a flange overlying each surface of the pencil body, at the end of the body opposite the lead end. This flange is formed in triangular pointed scallops, one of which overlies each of the four surfaces of the body of the pencil.

I claim:

The ornamental design for a pencil, as shown and described.

MARTIN E. TROLLEN.
